A. G. JOHNSON

BATHING CAP WITH GOGGLES

Filed Nov. 19, 1923

Inventor

Alphonzo Glendon Johnson

UNITED STATES PATENT OFFICE.

ALPHONZO GLENDON JOHNSON, OF CARDENAS, NORTH CAROLINA.

BATHING CAP WITH GOOGLES.

Application filed November 19, 1923. Serial No. 675,763.

To all whom it may concern:

Be it known that I, ALPHONZO GLENDON JOHNSON, a citizen of the United States, residing at Cardenas, in the county of Wake 5 and State of North Carolina, have invented a new, original, and useful Bathing Cap with Goggles, of which the following is a specification, reference being had to the accompanying drawing, forming part thereof.

10 The objects of the invention are to provide a water proof diving cap, having ear and nose covering and transparent eye covering portions for permitting the diver to see objects while underneath the surface of 15 the water, and at the same time keep the water out of his ears, nose and eyes.

Figures 1 and 2 are front and side views of the cap when in use. Figures 3 and 4 are side and front views of the cap when folded. 20 Figure 5 is an actual size drawing of the goggle set in the cap. Figure 6 is a cross section of Figure 5, drawn double size to show exact construction.

The numerals referring to the different 25 parts are respectively: 1, rubber skull-cap; 2 glass of goggle; 3, metal frame which holds glass; 4, rubber band acting as cushioning for number 1; 5, rubber band acting as a clamp to hold number 1 in place on number 30 3; 6, reinforcement band to make the skull-cap fit tight at the bottom.

The lower edge of the bathing cap is of 35 such circumference and so disposed relatively to the transparent eye covering portions that the edge passes around or encircles the face between the nose and mouth, or in other words, over the upper lip of the wearer. The cap tapers toward this edge, or in other words, this edge is somewhat contracted relatively to the part above, thereby 40 forming a water seal, i. e., it prevents the passage of water into the cap. It will be apparent that this location of the water seal portion, while shielding the eyes, ears and 45 nose from water, takes advantage of a contour of the face strikingly free of concavities which would be likely to permit the en-

trance of water, while at the same time allowing the wearer to breath through the mouth or talk at any time that his head is 50 above water without maneuvering the cap. Also by the particular location of the water sealing edge it is necessary to make such edge a normal length of but little less than the largest horizontal circumference of the 55 face whereby but little stretching is required in the placing or removing of the cap.

I am aware that prior to my invention goggles have been used on professional diving suits, gas masks, etc., and that bathing 60 caps are now on the market. I therefore do not claim such an invention broadly; but

I claim:

1. A waterproof bathing cap, comprising nose and ear covering and transparent eye 65 covering portions, said cap terminating at its lower edge in a face encircling water seal portion for preventing entrance of water into said nose, ear and eye covering portions, said lower edge terminating above the 70 mouth of the wearer when the cap is in a worn position.

2. A waterproof bathing cap comprising nose and ear covering and transparent eye covering portions, a face encircling water 75 seal part for preventing entrance of water into said portions, said water seal part including an upper lip engaging portion.

3. A waterproof bathing cap comprising nose and ear covering and transparent eye 80 covering portions, said cap tapering towards its lower edge and terminating at said edge in a face encircling water seal portion, said water seal portion including an upper lip engaging part.

4. An elastic rubber bathing cap, comprising nose and ear covering and transparent eye covering portions, said cap terminating in an elastic reinforced lower contracted edge, said edge including an upper lip 85 engaging portion and forming a water seal to prevent the entrance of water into said portions.

A. GLENDON JOHNSON
